EYE FOR TOY ANIMAL OR SIMILAR ARTICLE

Jacob Swedlin, Rockville Centre, N.Y., assignor to J. Swedlin, Inc., Brooklyn, N.Y., a corporation of New York

Filed May 11, 1964, Ser. No. 79,928

Term of patent 14 years

(Cl. D34—4)

FIG. 1

FIG. 1 is a top view of an eye for toy animal embodying my new design;

FIG. 2 is a front view thereof; and

FIG. 3 is a side elevational view thereof.

I claim:

The ornamental design of an eye for toy animal or similar article, substantially as shown.
